(57) **CLAIM**

The ornamental design for a gaming device, as shown and described.

DESCRIPTION

This application is related to the following commonly-owned co-pending design and utility patent applications: "Player Interface and Tray for a Gaming Device," Ser. No. 29/130,983; "Display and Mask for a Gaming Device," Ser. No. 29/130,997; "Display and Mask for a Gaming Device," Ser. No. 29/131,001; "Display and Mask for a Gaming Device," Ser. No. 29/131,076; "Tray for A Gaming Device," Ser. No. 29/130,981; "Player Interface With Bolster for a Gaming Device," Ser. No. 29/130,980; "Plate for a Midsection of a Gaming Device," Ser. No. 29/130,992; "Top Unit and Base for a Gaming Device," Ser. No. 29/130,979; "Base for a Top Unit of a Gaming Device," Ser. No. 29/130,982; "Gaming Device," Ser. No. 29/130,996; "Gaming Device Having a Door with a Moveable or Removable Bolster," Ser. No. 60/239,376; and "Protected Coin Tray For Use with a Gaming Device," Ser. No. 09/685,186.

FIG. 1 is a front perspective view of a gaming device of our new design, that portion of the gaming device shown in phantom is not part of the design sought to be patented and is provided for environmental purposes only;

FIG. 2 is a left side elevation view thereof, the right side being a mirror image thereof;

FIG. 3 is a top plan view thereof; and,

FIG. 4 is a front elevation view thereof.
